UNITED STATES PATENT OFFICE

2,452,920

METHOD AND APPARATUS FOR DRILLING
AND PRODUCING WELLSWalton E. Gilbert, Los Angeles, Calif., assignor
to Shell Development Company, San Francisco,
Calif., a corporation of Delaware

Application July 2, 1945, Serial No. 602,832

2 Claims. (CL 255-1.6) *166-35*

1

This invention pertains to the art of drilling and producing oil and gas wells, and relates more particularly to a method and apparatus for drilling, completing and producing wells which extend as a single well or borehole downwards from the surface and branch underground into a plurality of boreholes transverse or oblique to each other, each of said boreholes being auxiliary to all others in conveying to the surface through the common upper well bore the hydrocarbon fluid entering said branching boreholes from the formation.

As drilling depths increase, and drilling problems become correspondingly more serious, the desirability of having a plurality of tributary branch boreholes feeding a single main well bore becomes more and more apparent.

It is therefore an object of this invention to provide a method and apparatus whereby a well having a plurality of underground feeder boreholes branching off transversely to each other may be drilled, lined and produced by means of conventional tools and equipment normally used in drilling and production work.

It is also an object of this invention to provide a method and apparatus for drilling wells having a greater capacity than wells of the standard or single-borehole type, whereby wells may be advantageously drilled in formations having too low a yield for economical exploitation by conventional means.

It is also a particular object of this invention to provide a method and apparatus involving the use of gun-perforating technique for drilling and completing said multiple-borehole wells in productive zones or layers having a relatively small vertical thickness.

These and other objects of this invention will be understood from the following description taken with reference to the attached drawings, wherein:

Figs. 1, 2, 3 and 4 diagrammatically show successive stages in the drilling of a multiple bore well embodying the present invention;

Fig. 5 is a diagrammatic view in cross-section of a liner particularly suitable for use in practicing the present invention.

Referring to Fig. 1, a single well or borehole 10 is drilled from the surface, and has its upper portion lined with a casing string, for example a water string 3, a casinghead 1 being provided at the surface. After cementing the string 3, and drilling out the cement plug remaining within said string, the drilling is continued to a desired objective depth or level, for example through a producing zone or layer 21, the borehole being sunk either vertically, or preferably being deflected at

2 a desired level through a desired depth interval, as shown at 11, to extend obliquely or transversely to the vertical, as shown at 16 in the drawing. Any field tested means, such as whipstocks, 5 knuckle joints, etc., may be used to deflect the borehole.

The lower or uncased portion of the borehole is logged by any desired methods, such as mechanical or electrical coring, side wall sampling, formation testing, caliperizing, etc., and a junction zone, indicated at 13, is selected at a desired point below the cased portion of the well on the basis of the logging data. The junction zone should preferably be located either in a formation capable of contributing hydrocarbon fluids to the well, such as an upper producing layer, or in a formation of low permeability, so that the entry at this point of undesirable fluids, such as water, be restricted to a minimum. The permeability of the formation at the junction zone can further be decreased, if desired, by injecting into the formation certain sealing chemical or asphalt compounds or grouts, such as disclosed for example in U. S. Patents 2,138,713, 2,223,789, 2,169,458, 2,208,766 etc. It may likewise be desirable to underream the portion of the borehole extending through the junction zone, as shown at 15, in preparation for subsequent cementing, and treating, as will be described hereinbelow.

30 When the borehole 16 has been completed and conditioned, a liner string 9 is run thereinto, being hung from the casing by a hanger, diagrammatically shown at 5 and provided, if desired, with packing means 7. In the case illustrated, which shows a procedure for obtaining a satisfactory completion in a relatively narrow producing producing zone or layer 21, it will often be desirable to cement in the liner 9 throughout its entire length and squeeze cement and/or treat the junction zone, then gun-perforate opposite the layer 21, and test the production from the layer 21 to determine whether or not excessive amounts of gas or water accompany the oil. If due to any reason the produced fluids are unsatisfactory, the sequence of squeeze cementing, to close undesired perforations, reperforating, and retesting, may be repeated until satisfactory production is developed. However, depending upon the particular types and thicknesses of producing zones and current good practice in securing satisfactory completions therein, the liner string 9 may be either open or closed at the bottom by a plug or shoe 23 of any desired type, such as a cementing shoe. Necessary steps are taken for providing the liner 55 16 with perforations at desired levels, for example

with perforations 17 at the level of the junction-zone 13 and, except in the case of an open-bottom liner, with perforations 19 at the level of the producing zone 21.

For the purpose of this application, the term "providing with perforations" is intended to mean that the liner string is either made up at the surface and lowered into the well in such a manner as to comprise perforated, slotted, or wire-wrapped portions at the desired levels, for example those corresponding to the zones 21 and 13, or said liner is made up and lowered into the well as a blank string, and is perforated when in place by means of mechanical or gun perforators throughout the intervals of such zones 21 and 13. The portion 9A of liner 9, extending upwards from the bottom of the junction zone 13, as well as the hanger 5, should be made removable or of drillable materials, comprising alumnum, magnesium, plastics, etc.

With the liner 9 installed and cemented, if desired, and the perforations 17 properly placed, the junction zone may be squeeze-cemented therethrough and/or otherwise treated to minimize the permeabilities of adjacent strata.

After testing and developing satisfactory production from the zone 21 through the liner, the well's production is killed by conventional methods, the liner 9 is cleaned out, and an auxiliary or inner liner 29 is run thereinto, being hung within the outer liner 9 by means of a hanger 25, preferably provided with packer means in the same manner as hanger 5. The hanger 29 may, if desired, be anchored both against vertical and against rotational motion by means of slips having both vertical and horizontal teeth, such as disclosed, for example, in U. S. Patent 2,242,602. The liner 29 is run into the well in any desired manner, for example by attaching it, by means of a shear-pin 8, to the end of a drill or tubing string 6, as is customary in running whipstocks and as indicated in dotted lines in Fig. 5.

A preferred type of the inner liner 29 is shown in greater detail in Fig. 5 and may comprise an elongated tubular member closed at the bottom by a shoe or plug 28 and at the top by a transverse or slanting member 24, adapted to bridge the borehole along a curved surface transverse to its axis when the inner liner is installed in the outer liner as shown in Fig. 2. This bridging member is made of a drill-resisting material, such as steel, and has a convex upper face serving as a whipstock as indicated at 24A. The liner 29 is provided with perforations 27, to admit the formation fluids to the space within the liner. The bridging member 24 and the upper end of liner 29 may be run into the hole with perforations such as shown at 26 in Fig. 5, or the bridging member and the upper end of liner 29 may be free of such perforations, in which case the bridging member is run in as a blind plate as in the case illustrated in Fig. 2, the blind plate being perforated later as herein-after described. The inner liner 29 in its final form thus forms an elongated capsule member which is completely enclosed except for the perforations through which the well fluids are admitted thereto from the formation and delivered to the upper portion 10 of the borehole. It is however understood that in some cases a liner with an ordinary upper opening may be used instead of the liner 29 shown in Fig. 2, its upper end being bridged after installation in the borehole by means of a whipstock-shaped closure which can be perforated or removed.

After the inner liner 29 has been installed within

the outer liner 9, and its transverse face 24 has been properly oriented by means normally used for orienting whipstocks, such for example as described in U. S. Patent 1,806,509, a drill bit is lowered into the casing 3 and the upper drillable portion 9A of the outer liner 9 is drilled out or otherwise removed together with the hanger 5, shown in dotted lines in Fig. 2. Upon coming into contact with the oriented non-drillable whipstock member 24, the drill-bit is deflected and a second borehole 36, transverse to the first borehole 16, is drilled to a desired depth, for example, through the producing zone 21.

Referring to Fig. 3, if it is desired to limit the proposed well system to the two transverse boreholes 16 and 36, and to produce hydrocarbon materials only through these two boreholes, a liner 39 similar to liner 9 is lowered and installed in the borehole 36, being hung from the casing by means of a hanger identical with hanger 5 described with regard to Fig. 1.

The liner 39 may be provided with a bottom shoe or plug 43, and is likewise provided with perforations 37 at the level of the producing zone 21. Following the same procedure as for liner 9, the liner 39 may be cemented and treated for production. Subsequent to satisfactory testing, the holes 44 in the liner 39 and the holes 26 in the plate 24, which is substantially in abutment therewith, are perforated as by use of gun perforating equipment oriented into position opposite the plate 24.

If, however, it is contemplated to provide the present well system with more than two transverse or branch boreholes 16 and 36, the borehole 36, before the installation therein of the liner 39, is logged and a second junction zone 33 is selected and underreamed in the manner already described with regard to borehole 16.

The liner 39 is in such cases provided with further perforations 47 at the level of the second junction zone, and said zone is chemically treated and/or cemented in a manner also similar to that already described.

After completing the setting and testing of liner 39, an inner liner 59, similar to liner 29, is installed within the outer liner 39, and a third transverse borehole 56, shown in Fig. 4, is drilled by guiding a drill-bit past the transverse whipstock face 54 of the inner liner 59. A liner 69 is then lowered into the borehole 56 and is installed and cemented therein, likewise in a manner already described hereinabove. These operations may be repeated any desired number of times to give a well system having a single opening extending into the ground and branching underground into any desired number of auxiliary boreholes transverse to each other.

Assuming, however, that it is intended to limit the well system of Fig. 4 to the three transverse boreholes shown therein, the liner 69, extending into the last drilled borehole 56, may be suspended from the casing 3 by the customary hanger and packer means 5 and 7, and is provided with perforations 67 at the level of the production zone 21, and with a set of perforations, such as shown at 64 and 64A, at the level of each junction zone, said perforations being in effective register and providing for fluid communication with the mouth of each of the other transverse boreholes. In the case illustrated, the perforations 64 and 64A, and cooperating perforations in the bridging plates of liners 59 and 29, may be made, after testing production from the lower end of liner 69, by gun perforating.

If desired, a conventional inner liner, not shown, may be provided for the final liner 69 preferably not extending above the lowest junction zone.

After completion of the liner system, the customary tubing equipment may be lowered into the well, and hydrocarbon materials are produced from the well through proper connections installed at the casinghead 1.

It is obvious that the liners 8, 29, 39, 59 and 69 do not necessarily have to extend to the bottom of their respective transverse boreholes. Instead, short or partial liners, extending only part of the way from the junction zones to the producing zone, may be used, the lower portion of any or all of said boreholes forming in such case an open hole. It is obvious also the lower ends of inner liners such as 59 and 29 may be eliminated.

Further, it is obvious that by using suitable tubing and packer equipment in combination with the liner system of the present invention, all desired production and exploitation operations applicable to conventional wells, such as gas or liquid injection for purposes of pressure maintenance or secondary recovery, separate or combined multiple zone production, etc., may likewise be carried out in the well systems of the present invention. The usual methods of gravel packing are also adaptable to use with the method and apparatus for drilling and producing wells herewith described.

I claim as my invention:

1. The process of drilling a well, comprising the steps of drilling a single borehole from the surface to a desired depth, providing the lower portion of the borehole with a tubular lining, bridging the lined portion of the borehole along a surface transverse to the axis thereof, guiding a drillbit past the transverse bridging surface, thereby deflecting the bit and drilling a second borehole transversely to the first borehole, providing the second borehole with a second tubular lining extending above the point of junction of the two boreholes, and establishing fluid communication between the two boreholes by providing both the second tubular lining and the bridging surface

with perforations at the point of junction of the two boreholes.

2. For use in a well having a casing set in its upper portion and a plurality of feeder boreholes branching therebelow transversely to each other, 5 a liner system comprising a first liner member positioned in a feeder borehole opening to the well below the lower end of said casing, said liner having openings at its lower end for admitting 10 formation fluids thereinto, a perforated whipstock element closing the upper end of the liner member along a surface transverse to the axis of the liner member, means anchoring said liner member in the feeder borehole with said perforated whipstock element substantially aligned with the walls of 15 the well to form a deflecting surface masking the mouth of the feeder borehole at its junction with the well, a second liner member positioned in the well with an intermediate tubular portion thereof substantially in abutment with the perforated 20 whipstock element of the first liner, said second liner member having openings at its lower end for admitting formation fluids thereinto, means anchoring the upper end of the second liner member to the lower end of the casing, and radial 25 perforations in the intermediate tubular portion of the second liner member substantially in register with the perforated whipstock element of the first liner member whereby formation fluids entering the first liner member are delivered to the 30 surface through the casing together with the formation fluids entering the second liner member.

WALTON E. GILBERT.
